ATTACHMENT FOR BAG-FILLING TUBES

Alfred Tangdall, Superior, Nebr., assignor to Ideal Cement Company, Denver, Colo., a corporation of Colorado

Application November 23, 1938, Serial No. 242,060

4 Claims. (Cl. 226—48)

In the cement and other industries, the so-called Bates bag filling machine is used quite extensively, said machine having a tubular nozzle through which the cement or other finely divided product is discharged. When filling a paper bag, air must escape around the nozzle, and when filling a woven fabric sack, the air can, of course, escape through the mesh of the fabric. Therefore, the valve of the cloth bag is customarily smaller than the valve of a paper bag. In recent years, manufacturers of cement have ground their product much finer, causing difficulties in getting the bags to hold the necessary ninety-five pounds of cement, due to the fact that the fineness of the product prevents the air from escaping from the bags while they are being filled. To overcome this difficulty, the nozzle or filling tube, to my knowledge, has been provided with external ribs which prevent the filling opening of the bag from closing rather tightly around said nozzle or tube, allowing the air to escape more readily, but when the nozzle or tube is provided with such ribs, it cannot be advantageously used for filling fabric sacks. My invention, therefore, aims to provide a device which will readily hold the filling opening against snug closing around the filling tube or nozzle, when filling paper bags, and may be entirely detached from said filling tube or nozzle when the latter is to be used for filling fabric sacks.

With the foregoing in view, the invention resides in the novel subject matter hereinafter described and claimed, description being accomplished by reference to the accompanying drawings.

Fig. 1 is a side elevation showing the filling tube equipped with the attachment.

Fig. 2 is a longitudinal sectional view illustrating the manner in which the attachment prevents closing of the valved filling opening around the filling tube.

Fig. 3 is a bottom plan view of the tube and the attachment thereon.

Fig. 4 is a vertical transverse sectional view on line 4—4 of Fig. 2.

In the drawing above briefly described, the numeral 5 denotes the conventional filling tube or nozzle and 6 has reference to the usual flange or the like used in connecting the outer end of said tube or nozzle with the machine from which the cement or other finely divided product is discharged. The tube or nozzle 5 with the attachment thereon is insertable through the usual valved opening 7 of a Bates paper bag 8 or, with the attachment removed, is insertable into the

valve of a fabric sack. When filling a fabric sack, air can escape through the mesh of the fabric, but when filling a paper bag, previously sealed with the exception of the valved opening 7, it is necessary that the air escape through this opening. My attachment may then be used to prevent the opening from snugly closing around the tube or nozzle 5, and when the same tube or nozzle is to be used for filling fabric sacks, said attachment may be readily removed.

The attachment comprises a collar 9 to surround the outer end of the tube or nozzle 5, means 10 carried by said collar to enter the opening 7 and prevent snug closing of the latter around said tube or nozzle 5, and means 11 for releasably securing said collar 9 in place upon said tube or nozzle 5.

Preferably, the collar 9 is a one-piece continuous ring or band, and the releasable securing means 11 may well be formed by an ordinary set-screw. For illustrative purposes, I have shown an ordinary nut 12 welded or otherwise secured to the collar 9 in alignment with a radial opening 13 formed in said collar, the set-screw 11 being threaded through said nut 12 and received in the opening 13 to tightly abut the tube or nozzle 5 when tightened.

The means 10 preferably comprises a plurality of fingers welded or otherwise secured at one end to the collar 9 and projecting therefrom to lie against the lower portion of the tube or nozzle 5, to enter the opening 7, and to hold the valve 14 in spaced relation with said lower portion of said tube or nozzle. The inner extremities 15 of the fingers 10 are curved upwardly to prevent interference with insertion into the bag opening.

By providing the novel attachment shown and described or a substantial equivalent thereof, said attachment may be quickly and easily applied to the filling tube or nozzle 5, whenever its use is necessary, that is, when filling paper bags through the usual valved filling opening. Whenever the use of the attachment is not required, that is, when filling fabric sacks, it may be quickly and easily removed.

The details disclosed have proven to be of advantage from standpoints of manufacture and use and are preferably followed. However, within the scope of the invention as claimed, minor variations may, of course, be made.

What is claimed is:

1. An attachment for a bag-filling tube insertable into an opening in the bag, said attachment comprising a collar to surround the outer end of the tube, means on said collar to prevent closing

- of the bag opening around the tube, allowing air to escape from the bag as the latter is being filled, and releasable means for detachably securing said collar in place upon the tube.
5. An attachment for a bag-filling tube insertable into an opening in the bag, said attachment comprising a collar to surround the outer end of the tube, spaced fingers secured to said collar and projecting therefrom to extend along the tube and into the bag opening to prevent this opening from closing around the tube, thereby permitting air to escape from the bag as the latter is being filled, and releasable means for detachably securing said collar in place upon the tube.

3. An attachment for adapting to filling paper valve bags a bag-filling tube normally adapted for filling cloth bags, said attachment comprising spaced fingers, a support for detachably holding the fingers on the exterior of the tube and longitudinally thereof, and a single screw for securing the support in operative position with respect to the tube.

4. An attachment in accordance with claim 3 and the said support comprising a collar adapted to fit around the rear of the tube, and said single screw being a set screw through the underside of the collar.

ALFRED TANGDALL.
